COMBINED DENTAL LIGHT AND SUPPORT THEREFOR

John A. Maurer and Dean H. Buchtel, Canton, Ohio, assignors to The Weber Dental Manufacturing Company,
Canton, Ohio, a corporation of Ohio

Filed Nov. 17, 1969, Ser. No. 20,123

Term of patent 14 years

Int. Cl. D26—02

U.S. Cl. D48—20

FIG. 1 is a perspective view of a combined dental light and support therefor, showing our new design;

FIG. 2 is a greatly enlarged front perspective view thereof; and

FIG. 3 is an enlarged rear perspective view thereof.

The support is fragmentarily shown in FIGS. 2 and 3 for convenience of illustration.

We claim:

The ornamental design for a combined dental light and support therefor, substantially as shown and described.
